UNITED STATES PATENT OFFICE.

HENRY MANTHEY, OF LANSING, MICHIGAN, ASSIGNOR TO THE "NEW-WAY" MOTOR COMPANY, OF LANSING, MICHIGAN.

CHARGE-FORMING DEVICE FOR INTERNAL-COMBUSTION ENGINES.

1,303,703.

Specification of Letters Patent. Patented May 13, 1919.

Application filed January 12, 1918. Serial No. 211,557.

To all whom it may concern:

Be it known that I, HENRY MANTHEY, a citizen of the United States, residing at Lansing, in the county of Ingham and State of Michigan, have invented certain new and useful Improvements in Charge-Forming Devices for Internal-Combustion Engines, of which the following is a specification.

This invention relates to improvements in charge forming devices for internal combustion engines.

My present improvements are especially designed by me for embodiment in the structure shown in my application for Letters Patent filed April 17, 1917, Serial No. 162,648, although they are capable of embodiment and desirable for use in other relations.

The main objects of this invention are: 20 First, to provide an improved fuel feeding means in which a fuel such as kerosene may be employed for the normal running of the engine and a lighter fuel employed for starting the engine.

25 Second, to provide an improved structure having these advantages which is very simple in its structure and very convenient in use.

Further objects, and objects relating to 30 structural details, will definitely appear from the detailed description to follow.

I accomplish the objects of my invention by the devices and means described in the following specification. The invention is 35 clearly defined and pointed out in the claims.

A structure which is a preferred embodiment of my invention is clearly illustrated in the accompanying drawing forming a part of this specification, in which:

40 Fig. I is a side elevation of a structure embodying the features of my invention, certain parts being broken away or omitted.

Fig. II is an enlarged detail vertical section on a line corresponding to line 2—2 of 45 Fig. III.

Fig. III is a detail horizontal section on a line corresponding to line 3—3 of Figs. I and II.

Fig. IV is a detail plan view showing the 50 closure for the opening through which the lighter fuel is drained to the fuel reservoir.

Fig. V is a detail section on a line corresponding to line 5—5 of Fig. IV.

In the drawing, similar reference characters refer to similar parts throughout the

several views, and the sectional views are taken looking in the direction of the little arrows at the ends of the section lines.

Referring to the drawing, the carbureting chamber designated generally by the numeral 1, is provided with inlet connections, preferably as shown in my said application for Letters Patent. However, as these connections form no part of my present invention, they are not illustrated or described herein. The nozzle 2 is arranged to receive its fuel from the fuel reservoir 4. This reservoir has an overflow compartment 5 formed in one corner thereof by the partition or overflow wall 6. To the bottom of this I connect the overflow pipe 7. The feed reservoir has an opening 8 in the bottom thereof adapted to receive the pump cylinder 9. This pump cylinder is carried by the cylinder member or casting 10, being preferably formed integrally therewith as illustrated. The cylinder member has an inlet passage 11 therein to which the inlet pipe 12 is connected, a coupling 13 for the pipe 12 being threaded into the casting. 80

At the lower end of the cylinder 9 is a valve seat 14 for the inlet valve 15. The plunger 16 is hollow or chambered, being open at its inner end and provided with a valve seat 17 for the valve 18. Coiled spring 19 holds this valve 18 on its seat. A coiled spring 20 seating in the plunger insures the return of the plunger. The upper end of the plunger projects through the top wall of the reservoir so that it may be actuated 90 from the rocking lever 21 which is pivoted at 22 to be engaged by the push rod 23.

When it is desired to lock the pump in inoperative position the latch 24 is adjusted to force the lever 21 and the plunger downward thus raising the lever out of engagement with the push rod 23. 95

The reservoir is provided with a drain opening or port 25 which is connected with the inlet passage 11 by the drain passage 26 in the cylinder member. The drain opening 25 is controlled by the needle valve 27 disposed in an inclined position so that its threaded stem projects through the side wall of the reservoir above the fuel level thereof. 105 When this drain valve is open the fuel flows from the reservoir into the inlet passage and thence to the inlet pipe 12, the drain being connected to the inlet passage in advance of the inlet valve 15. This permits the drain- 110

ing of the heavier fuel such as kerosene from the reservoir when it is desired to charge the engine and filling with lighter fuel, such as gasoline. An opening 28 is provided in the top of the reservoir for the introduction of the lighter fuel. This opening is normally closed by the cover 29.

By thus arranging the parts I provide a structure which is simple and not likely to 10 get out of repair in use. At the same time it is capable of rapid and convenient manipulation. The device is preferably operated as follows: Assuming that the engine has been in operation and has stopped with 15 the reservoir full of kerosene and it is desired to restart the engine, the valve 27 is opened to allow the kerosene to drain from the reservoir, the valve is then closed and the reservoir filled with gasoline or other 20 more volatile hydrocarbon for starting, the opening 28 being provided for this purpose. The pump is rendered inoperative by means of the latch 24 which is adjusted to force the lever 21 and the pump plunger downward, thus raising the lever out of its co-acting relation with the push rod. The supply of gasoline is maintained sufficiently to feed through the nozzle when the engine is 25 started and warmed the latch is raised to 30 allow the pump to act and the kerosene to feed into the reservoir. The nozzle 2 communicates with the reservoir through the passage or bore 2', see Fig. III.

I have illustrated my improvements in the 35 form in which I have embodied the same in practice. I have not attempted to show other embodiments or adaptations which I contemplate as I believe the disclosure made 40 will enable those skilled in the art to which my invention relates to embody or adapt the same as may be desired.

Having thus described my invention, what I claim as new and desire to secure by Letters Patent is:

45 1. In a structure of the class described, the combination of a fuel reservoir having a drain opening and a pump cylinder opening in its bottom and provided with an overflow compartment, a pump cylinder member secured on the bottom of said reservoir and 50 provided with a cylinder projecting through said pump cylinder opening into said reservoir, said cylinder member having an inlet passage with a check valve seat at the lower 55 end of the cylinder and a drain passage connecting said drain opening with said inlet passage below said check valve seat, a check valve arranged on said seat, a pump plunger disposed through the top of the 60 reservoir to coat with said cylinder, a valve for said drain opening disposed within said reservoir with its stem projecting through the wall thereof, and an overflow pipe connected to said overflow compartment.

65 2. In a structure of the class described, the

combination of a fuel reservoir having a drain opening and a pump cylinder opening in its bottom and provided with an overflow compartment, a pump cylinder member secured on the bottom of said reservoir and 70 provided with a cylinder projecting through said pump cylinder opening into said reservoir, said cylinder member having an inlet passage and a drain passage connecting said drain opening with said inlet passage, a 75 valve for said drain connection, and an overflow pipe connected to said overflow compartment.

3. In a structure of the class described, the combination of a fuel reservoir having a 80 drain opening and a pump cylinder opening in its bottom provided with an overflow determining the normal level of the fuel therein, a pump cylinder member with a cylinder projecting through said pump cyl- 85 inder opening into said reservoir, said cylinder member having an inlet passage with a check valve seat at the lower end of the cylinder and a drain passage connecting said drain opening with said inlet passage below 90 said check valve seat, a check valve arranged on said seat, a pump plunger coacting with said cylinder, and a valve for said drain connections.

4. In a structure of the class described, the combination of a fuel reservoir having a drain opening and a pump cylinder opening in its bottom and provided with an overflow determining the normal level of the fuel therein, a pump cylinder member with a cylinder projecting through said pump cyl- 100 inder opening into said reservoir, said cylinder member having an inlet passage and a drain passage connecting said drain opening with said inlet passage, a pump plunger coacting with said cylinder, and a valve for 105 said drain connections.

5. In a structure of the class described, the combination of a fuel reservoir having an overflow compartment and a drain opening outside of said compartment, a fuel pump provided with an inlet valve and inlet passage, a drain passage connecting said drain opening with said inlet passage in front of said inlet valve, a valve for said drain connection, and an overflow pipe connected to 110 said overflow compartment.

6. In a structure of the class described, the combination of a fuel reservoir having an overflow compartment and a drain opening outside of said compartment, a fuel passage, a drain passage connecting said drain opening with said inlet passage, a valve for said drain connection, and an overflow pipe connected to 115 said overflow compartment.

7. In a structure of the class described, the combination of a fuel reservoir having an overflow determining the normal level of the fuel, a fuel pump provided with an inlet valve and an inlet passage, a drain 120

125

connection for said reservoir to said inlet passage opening into said inlet in front of said inlet valve, and a valve for said drain connection.

5 8. In a structure of the class described, the combination of a fuel reservoir having an overflow determining the normal level of the fuel, a fuel inlet passage, a drain connection for said reservoir to said inlet pas-

sage, and a valve for said drain connection. 10

In witness whereof, I have hereunto set my hand and seal in the presence of two witnesses.

HENRY MANTHEY. [L. S.]
